UNITED STATES PATENT OFFICE.

JOHN QUINCY REED, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 15,023, dated May 27, 1884.

Application filed March 27, 1884. Term of patent 3½ years.

To all whom it may concern:

Be it known that I, JOHN QUINCY REED, of the city, county, and State of New York, have invented and produced a new and original Design for a Pattern of a Lady's Costume, (numbered 9,166;) and I do hereby declare that the engraved prints accompanying this specification convey to any one accustomed to using paper patterns a clear understanding of how a

garment made up by the pattern will appear.

The design shows a round walking-skirt and an overdress; the skirt displays a right front-drapery laid in deep crosswise plaits, and having the appearance of being overlapped along its plaited front edge by a left front-drapery that exhibits a scalloped front edge and drap-

ing plaits in its back edge; the overdress displays closely-fitted basque-fronts; a closely-fitted polonaise-back exhibiting under-folded plaits below the waist-line of its middle three 20 seams, and loopings at each side and in its front edges; coat-sleeves, and a standing collar.

What I claim as my invention, and desire to secure by Letters Patent, is—

The design for a lady's costume, as shown in 25 the engraved prints accompanying this specification.

JOHN QUINCY REED.

Witnesses:

ALFRED FRANCIS,
JOHN HENRY DRURY.
